FILLING MACHINE WEIGHING STATION

Doyle R. Hudson, West Monroe, La., assignor to
Olinkraft, Inc., West Monroe, La.

Filed Feb. 10, 1975, Ser. No. 548,479

Term of patent 14 years

Int. Cl. D10—04

U.S. Cl. D10—87

FIG. 1

FIG. 2

FIG. 3

FIG. 4

FIG. 5

FIG. 1 is a right side elevational view of a filling machine weighing station showing my new design, the left side being substantially a mirror image thereto;

FIG. 2 is a front elevational view taken along line 2—2 of FIG. 1;

FIG. 3 is a rear elevational view taken along line 3—3 of FIG. 1;

FIG. 4 is a bottom plan view taken along line 4—4 of FIG. 1; and

FIG. 5 is a top plan view taken along line 4—4 of FIG. 1.

I claim:

The ornamental design for filling machine weighing station, substantially as shown and described.
